(57) **CLAIM**

The ornamental design for a lever compression latch, as shown and described.

DESCRIPTION

FIG. 1 is a front isometric view of a lever compression latch, according to a first exemplary embodiment of the invention; FIG. 2 is a front elevation view thereof; FIG. 3 is a rear isometric view thereof; FIG. 4 is a rear elevation view thereof; FIG. 5 is a left elevation view thereof; FIG. 6 is a right elevation view thereof; FIG. 7 is a top plan view thereof; and, FIG. 8 is a bottom plan view thereof.

In the drawings, the broken lines indicate environmental structure that forms no part of the claimed design. The dash-dot lines indicate the boundaries of the claimed subject matter. The black shading in the drawings of FIGS. 1, 2, and 5–8 represents color contrast and is not limited to any particular color or color combination.
